SHIELD FOR LINOLEUM COVERED
SINK TOPS

Julius F. Kirvay, South Euclid, Ohio

Application March 17, 1950, Serial No. 150,213

1 Claim. (Cl. 4—187)

1

This invention relates to a protective shield and drain device for linoleum covered sink tops and, as one of its objects, provides an improved construction for a device of this kind such that it can be quickly and easily installed, will present a neat and attractive appearance and will cover and protect the linoleum so as to prevent deterioration thereof as the result of repeated wetting by water being spilled thereon or leaking from the water supply faucets and delivery spout.

Another object of this invention is to provide an improved shield and drain device of this character which can be economically produced from sheet metal or other suitable sheet material and which has integrally formed water barrier portions for confining the water on the exposed surface of the device and facilitating drainage thereof into the sink.

A further object of the invention is to provide a protective shield and drain device of this character which comprises a pair of cover members, one being a substantially flat horizontal cover member for application to a linoleum covered horizontal portion of the sink top and the other being an upright cover member for application to a linoleum covered upright portion of the sink top and in which adjacent edges of the horizontal cover member and the upright cover member have novel cooperating portions.

Other objects and advantages of this invention will be apparent from the following detailed description and the accompanying sheet of drawings in which:

Fig. 1 is a perspective view of a linoleum covered sink top showing the protective shield and drain device of the present invention applied thereto;

Fig. 2 is a vertical section taken through the sink top with the protective shield and drain device thereon, as indicated by section line 2—2 of Fig. 1;

Figs. 3 and 4 are perspective views showing the horizontal cover member and the upright cover member in detached relation;

Fig. 5 is a transverse sectional detail taken through the upstanding water barrier bead of the horizontal cover member, as indicated by section line 5—5 of Fig. 3;

Fig. 6 is a fragmentary perspective view on a somewhat larger scale and showing the cooperating engagement of adjacent edge portions of the horizontal and upright cover members; and

Fig. 7 is a vertical section taken through the cooperating edge portions of the horizontal and

upright cover members and illustrating a modified construction.

In Figs. 1 and 2 of the drawings, a sink top 10 is shown forming a support for a conventional kitchen sink 11 and comprising a horizontal top portion 12 and an upright wall portion 13. The sink top 10 is provided with a linoleum covering 14 which, in this instance, extends in continuous relation over the horizontal top portion 12 and upwardly over the rear or upright wall portion 13. The sink top 10 is also provided with water delivery means comprising a spout 15 extending forwardly in overhanging relation to the sink 11 and a pair of hot and cold water faucets 16 and 17.

The water delivery means may also include a hollow valve body 18 located beneath the horizontal top portion 12 and having water supply pipes 19 connected therewith. The valve body 18 contains the valve mechanisms of the hot and cold water faucets 16 and 17 and also includes upstanding hollow stem portions 20 extending through spaced openings 21 of the horizontal top portion 12 at the locations of the spout 15 and the faucets 16 and 17. The stem portions 20 are suitably threaded and have lock nuts 22 applied thereto by which the valve body 18 is positioned relative to the horizontal top portion 12 and suspended thereon. The faucets 16 and 17 include actuating handles 16a and 17a and valve stems 23 adapted to be actuated by such handles and extending downwardly into the valve body 18 through the hollow stem portions 20 and through suitable packing glands 24.

The protective shield and drain device provided by this invention comprises a generally flat horizontal cover member 25 which is applied to the linoleum covering 14 so as to lie against and extend over a substantial portion of the linoleum covering which is located in surrounding relation to the faucets 16 and 17 and the upright portion of the delivery spout 15. The horizontal cover member 25 can be made from non-corrosive sheet metal, or from other suitable non-corrosive sheet material such as plastic or rubber. This cover member can be stamped from such sheet metal by suitable metal working dies or can be molded from the plastic or rubber sheet material by suitable molding dies.

The portions of the horizontal cover member 25 which surround the openings 26 are deflected upwardly so as to form an upstanding annular flange or ferrule 27 in surrounding relation to each of the stem portions 20. These ferrules form water barriers on the upper or ex-

posed surface of the horizontal cover member 25 which tend to deflect water away from the openings 26 so as to prevent such water from passing through the cover member and causing deterioration of the linoleum covering 14. To assist in preventing water from passing downwardly through the openings 26, a suitable sealing material or waterproof cement 28, such as asphalt, is applied to these openings so as to substantially fill the space between the ferrules 27 and the stem portions 20 of the valve body 18.

As shown in the drawings the horizontal cover member 25 has the front edge thereof deflected downwardly in angular or curving relation to form a downwardly extending drainage lip 29 adapted to overhang the adjacent edge of the sink 11 to facilitate drainage of water from this cover member into the sink. The openings 26 of the cover member 25 are made considerably larger in size than the stem portions 20 and the lock nuts 22 so as to permit lateral shifting of this cover member on the horizontal top portion 12 for bringing the drainage lip 29 into a snug engagement with the edge of the sink top or with the rim of the sink 11, as shown in Fig. 2. The enlarged openings 26 will thus permit proper positioning of the drainage lip 29 with respect to the edge of the sink top, regardless of variations in the spacing of the faucet members 16 and 17 relative to the edge of the sink top as may occur in different sink installations.

As shown in the drawings other portions of the horizontal cover member 25 are deflected upwardly out of the general plane of this member to form an upstanding continuous bead 30 which constitutes a water barrier on the exposed surface of this cover member. The bead 30 is here shown as comprising a longitudinal bead 30a extending along the rear edge of the cover member 25 and forwardly extending beads 30b located adjacent the ends of the cover member. The beads 30b are here shown as including inwardly offset bead portions 30c and forwardly extending end portions 30d which are carried forwardly and downwardly on the drainage lip 29.

From the construction described above for the horizontal cover member 25, it will be seen that the portion of the upper surface of this cover member which surrounds the faucets 16 and 17 and the upright portion of the delivery spout 15 lie within the area enclosed by the bead 30 such that water spilled onto the cover member, or leaking from the spout and faucet members will be prevented from coming into contact with the linoleum covering 14 and will drain freely from the lip 29 into the sink 11. If desired, a thin layer (not shown) of a suitable cement such as that used to seal the openings 26, can also be used between the linoleum 14 and the cover member 25 for attaching the latter to the sink top. In installing the cover member 25 on the sink top in the relation just described above, the faucet handles 16a and 17a, as well as the faucet housings 16b and 17b, are removed to permit the cover member to be moved into position against the linoleum, after which these handles and housing members are replaced so as to occupy the positions shown in Figs. 1 and 2.

For use on sink tops which include the upright wall portion 13, the shield and drain device of this invention may also include an upright cover member 33 which is applied to the linoleum covering of this upright wall portion and can be conveniently referred to as a cover section or member. The upright cover member 33

can also be made of non-corrosive sheet metal, or other suitable non-corrosive sheet material such as plastic or rubber, and includes a substantially flat upright wall portion 34 of a length corresponding with the horizontal cover member 25 and of a height or width to extend over and lie against the linoleum covering of the upright wall portion 13. The upright cover member 33 also includes a forwardly extending lateral flange 35 along the lower edge thereof which cooperates with the adjacent rear edge of the horizontal cover member 25. In this instance the lateral flange 35 of the cover member 33 is connected with the upright portion 34 by an arcuate connecting portion 36.

Since in different sink installations the location of the upright wall portion 13 may vary with respect to the hollow stem portions 20 of the valve body 18, this invention provides a novel joint between the horizontal cover member 25 and the upright cover member 33 which will accommodate such variations in spacing. This novel joint is formed by the bead 30a of the horizontal cover member 25 and a bead 37 provided on the lateral flange 35 and extending along the forward edge thereof. The bead 37 overlaps the bead 30a, as shown in Fig. 2, and has a recess 37a in the underside thereof which has a transverse width considerably greater than the transverse width of the bead 30a such that the latter bead can occupy different relative positions in this recess. The recess 37a will thus permit shifting of the upright cover member 33 relative to the horizontal cover member 25 during installation as may be necessary to locate the portion 34 of the upright cover member against the upright wall 13.

To permit the overlapping relation of the bead 37 with respect to the bead 30a, suitable recesses 40 or notches 38 are formed in the edge of the bead 37 adjacent the ends of the upright cover member 33, as shown in Figs. 4 and 6. When the upright cover member 33 has been installed in the position shown in Figs. 1 and 2, the recesses 38 will engage the beads 30b in straddling relation thereto and such engagement will permit the lower edge of the bead 37 to lie tightly against the surface of the horizontal cover member 25. This engagement of the notches 38 with the beads 30b also provides a means for locating the upright cover member 33 in registering aligned relation with respect to the horizontal cover member 25.

The upright cover member 33 can be attached to the upright wall portion 13 by the use of a thin layer (not shown) of a suitable cement between this member and the linoleum covering 14, such as the waterproof cement mentioned above. Although the cover members 25 and 33 have been described as being secured in place by cement, suitable fastening members, such as nails or screws, can be used in place of or in addition to such cement. Waterproof cement is also provided in the bead recess 37a to form a sealing means 39 for the joint formed by the beads 30a and 37.

Instead of using a joint between the upright covering member 33 and the horizontal cover 25 which includes the overlapping relation explained above for the bead 37, a modified form of the joint can be used as shown in Fig. 7. In this modified form of joint the upright cover member 33 is provided with a flat forwardly extending lateral flange 40 whose edge is disposed in abutting relation to the bead 30a. Likewise, it should be understood that, in some instances, the end

beads 30b can be omitted from the horizontal cover member 25 and the rear bead 30a can be carried out to the ends of this cover member. When the horizontal cover member 25 carries only the rear bead 30a, the notches 38 can be omitted from the bead 37 of the upright cover member 33.

In the embodiment of the invention illustrated in the drawing the shield and drain device is shown as comprising the horizontal and upright cover members 25 and 33, but it should be understood that in some instances the horizontal cover member 25 alone will be sufficient and therefore, if desired, the upright cover member 33 can be omitted.

From the foregoing description and the accompanying drawings it will now be readily understood that this invention provides a protective shield and drain device for a linoleum covered sink top which will prevent deterioration of the linoleum covering as the result of repeated wetting by water spilled thereon, or by water leaking from the faucets and delivery spout. It will also be seen that because of the drainage lip and water barrier portions provided on the horizontal cover member, the water which spills or drips onto this cover member will be confined and directed so that it will drain into the sink 11. Furthermore, it will be seen that when this protective shield and drain device is made of sheet metal and provided with a bright finish, as afforded by chromium plating, this device will give the sink top a neat and an attractive appearance. Likewise, it will be understood that when this protective shield and drain device is made from rubber or other plastic material it can be made in various desired colors.

Although the protective shield and drain device of this invention has been illustrated and described herein to a somewhat detailed extent, it will be understood, of course, that the invention is not to be regarded as being limited correspondingly in scope but includes all changes and modifications coming within the terms of the claim hereof.

Having thus described my invention, I claim:

A protective shield and drain device for use on a sink top having horizontal and upright linoleum covered wall portions and water delivery means extending through the linoleum covered horizontal wall portion, comprising a generally flat horizontal cover member made of non-corrosive sheet material and being of a

length and width to extend over and lie against a substantial area of the linoleum surrounding said delivery means, and an upright cover member made of non-corrosive sheet material and having a generally flat upright portion of a length and height to extend over and lie against a substantial area of the linoleum of the upright wall portion, said horizontal cover member having a front edge portion deflected downwardly to define an integral drainage lip for drainage of water from the device at said front edge and integral upstanding continuous bead means forming a water barrier on the upper surface of said horizontal cover member and including an edge bead extending along the rear edge thereof and other bead means adjacent the ends of said horizontal cover member and extending forwardly from the ends of said edge bead to said drainage lip, said horizontal cover member also having openings therein located inwardly of its edges to accommodate said delivery means and upstanding integral annular portions surrounding said openings and defining ferrules adapted to surround said delivery means and form water barriers therearound, said upright cover member having a forwardly extending integral lateral flange at the lower edge of said upright portion and the forward edge of said lateral flange having a longitudinal hollow connecting bead therein adapted to overlie the edge bead of said horizontal cover member, said connecting bead having a recess in the underside thereof which is of a transverse width substantially greater than the transverse width of said edge bead to permit shifting of said upright cover member relative to said horizontal cover member after the latter has been applied to said horizontal wall portion and said connecting bead also having notches in the forward edge thereof adapted to straddle said other bead means of the horizontal cover member.
